PLEASANT PUFF OVERDRAFT PIPE

John B. Swan, Gladstone, Mich.

Application October 30, 1942, Serial No. 463,960

1 Claim. (Cl. 131—202)

This invention relates to a pleasant puff over-draft pipe.

An object of the invention is the construction of a novel pipe whereby the user can enjoy a pleasant smoke, by reason of a novel absorbent device being used in the pipe, with means for causing the tobacco to burn with reasonable freedom, which altogether produces ideal results.

Another object of the invention is the construction of a novel absorbent device in a pipe, which will prevent objectionable juices or the like from being drawn into the mouth of the smoker or user.

A still further object of the invention is the construction of a novel over-draft pipe which is comparatively inexpensive to manufacture, efficient in operation and of a long life.

With the foregoing and other objects in view, my invention comprises certain novel constructions, combinations, and arrangements of parts as will be hereinafter fully described, illustrated in the accompanying drawing, and more particularly pointed out in the appended claim.

In the drawing:

Figure 1 is a view partly in elevation and partly in longitudinal section of a pipe constructed in accordance with the present invention.

Figure 2 is an enlarged sectional view taken on line 2—2, Figure 1, and looking in the direction of the arrows.

Figure 3 is a perspective view of the absorbent device, without the cheese cloth or cotton batten unit thereon.

Figure 4 is a plan view of a piece of cotton batten, while

Figure 5 is a similar view of a piece of cheese cloth.

Referring to the drawing by numerals, in which drawing I have shown the preferred embodiment of my invention, 1 designates the bowl, which is provided with an integral laterally-extending neck 2. The bowl 1 is also provided with an inlet aperture 3, which permits air to be drawn into the bowl by the user, whereby the tobacco burns comparatively freely, without going out; so often smokers are annoyed by the fire or burning tobacco dying out, but this is practically eliminated in my improved pipe.

An over-draft tube 4 extends into the bowl 1, the inner end of said tube terminating approximately one-eighth of an inch from the bottom or inner face of the bowl. The outer end of tube 4 extends into the neck 2 near its outer end. A detachable mouthpiece 5 has a reduced

portion 6; reduced portion 6 has an aperture 7 that registers with the outer end of over-draft tube 4, Fig. 1, whereby the smoke is drawn from the bowl into the mouthpiece through said over-draft tube 4.

An absorbent device 8 is placed in the pipe, as clearly shown in Figure 1, for the purpose of absorbing the moisture or juices that ordinarily collect in the bottom of a pipe. This novel absorbent device 8 comprises a coil spring body 9, the outer coil 10 being provided with a sharp impaling point 11; the inner coil 12 terminates in an elongated integral handle 13, which handle is on a line with the central longitudinal axis of the coil spring body 9. This admirably places the handle in position to be easily inserted and centers in the mouthpiece 5, as clearly shown in Figure 1. The elongated handle 13 terminates at its outer end in an integral elongated loop grip 14. When the mouthpiece 5 is detached from the neck 2 the operator can secure an efficient grip on the absorbent device at 14 to remove the absorbent device, or to insert it, after it has been removed from the assembled position. I place an absorbent piece or sheet upon the coil spring body, such as cotton batting 15 or cheese cloth 16. The unit 15 or 16 is best wrapped upon the coil spring body by imparting rotary movement to the body thereby impaling an end on the point 11 and then continuing rotary movement to the body, thereby winding the sheet around lightly until enough has been wound on to fill the neck 2 of the pipe, then press all around the coil spring body 9 until the winding of the absorbent unit is pressed in between the coils; this presses down the wrapping so it comes nearly together, or entirely so, on the inside of the coil, making an excellent filter or absorbent. The impaling point 11 is near the center longitudinal axis of the body 9, whereby the absorbent unit 15 or 16 is admirably placed and held for the wrapping function.

I plan on having preferably six of the absorbent devices 8 (Fig. 3) with each pipe sold, so the smoker can take out his absorbent device or filter, every night, and by putting it in vinegar a few hours, it will rinse out easily. Therefore, the user of the pipe can have a clean absorbent device every day, at a very small cost and little effort.

The inlet aperture or vent hole 3 will allow the air to enter below the fire, which will make a cool smoke when the smoker first starts the pipe. When first lighting the pipe the user gives three or four brisk puffs until the tobacco is

all on fire, and then he can puff easily, whereby he will obtain an ideal smoke.

While I have described the preferred embodiment of my invention and illustrated the same in the accompanying drawing, certain minor changes or alterations may appear to one skilled in the art to which this invention relates, during the extensive manufacture of the same, and I, therefore, reserve the right to make such alterations or changes as shall fairly fall within the scope of the appended claim.

What I claim is:

As a new article of manufacture, an overdraft pipe provided with an absorbent device, said absorbent device comprising a body of a series of 15 spring coils, said body having its outer coil par-

allel throughout its length with the other coils and terminating in a sharp impaling point turned inwardly near the longitudinal axis in convolution with the rest of said coil, said body having its inner coil terminating in an integral elongated handle, said handle extending or centered with the longitudinal axis of said body, said handle provided at its outer end with a horizontal elongated loop grip, and an absorbent sheet impaled on said sharp point by rotating said body, whereby the sheet is rolled around the whole of said body with portions of said sheet within spaces formed by said coils and also covering the exterior surface of said body.

JOHN B. SWAN.
